COLLIER V. HEMENWAY, OF NEW LONDON, OHIO, ASSIGNOR TO HIMSELF
AND A. A. POWERS, OF SAME PLACE.

Letters Patent No. 101,616, dated April 5, 1870.

IMPROVEMENT IN BRICK-MACHINES.

The Schedule referred to in these Letters Patent and making part of the same.

To all whom it may concern:

Be it known that I, COLLIER V. HEMENWAY, of New London, in the county of Huron and State of Ohio, have invented a certain new and improved Brick-Machine; and I do hereby declare that the following is a full, clear, and complete description of the same, reference being had to the accompanying drawings making part of this specification, in which drawings—

Plate 1—Figure 1 is a front elevation of the machine.

Figure 2, a view of the top.

Figure 3, a view of the under side.

Figure 4, a detached section.

Plate 2—Figure 5 is a side view.

Like letters of reference refer to like parts in the several views.

Objective.

This invention relates to a machine for molding and pressing bricks, the press being worked by a pair of segment gears or levers engaging in a vertical standard and operated by a series of revolving radial arms, whereby said standard is raised and lowered for pressing the bricks, as hereinafter more fully described.

Descriptive.

In fig. 1, A represents a case or body of the machine into which the clay is thrown to be reduced to a proper consistency for molding, and which is done by a system of revolving radial arms, as ordinarily practiced.

At the lower front end of the case is the press-box B, fig. 5, into which the clay is received from the case and forced into the mold C, immediately under said box, by means of the follower fitted therein D, fig. 2, and attached to the lower end of the standard E, whereby it is operated by the segmental gear or levers F G, fig. 1, as hereinafter shown.

H is a shaft, standing vertically in the center of the case, to the upper end of which is secured a wheel, I, to which motion is given by a pinion, J, secured to the shaft K.

To said wheel I are pivoted six radial arms L M, all of which may be turned up to a vertical position, as shown in figs. 1 and 5.

It will be observed that four of said arms L are arranged at right angles to each other, as shown in fig. 2, whereas the two arms M, which are shown as being turned up, and represented as extended by the dotted lines c, in fig. 2, together with the arm L, are arranged equidistant in the wheel, forming trinity of arms instead of a quartering, as in the above instance, the purpose of which will presently be shown.

To the lower end of the shaft H, immediately under the bottom of the case, is secured a wheel, N, fig.

3, in which is arranged a duplication of the pivoted arms just described, and with which they relatively co-operate in their numerical number, and which are also indicated by corresponding letters.

Below said wheel is a shaft, O, having its bearings in the sides of the base of the case.

To said shaft is secured an arm, P, fig. 2, to the upper end of which is pivoted a slide, Q, a front view of which is shown in fig. 1.

The position of the arm and slide, when at rest, is that shown in fig. 2, and is thus assumed by the spring R, fig. 1.

Operative.

The operation of this machine is as follows, viz:

The clay, on being properly prepared, is then forced from the case into the press-box referred to, under which is inserted a mold S. Through the opening T in the side of the case, a second mold, U, is inserted between that immediately under the press-box and the slide Q. This being done, the clay is forced from the box into the mold underneath by the follower D, which is driven downward from the position seen in fig. 1 to that shown in fig. 4, thereby forcing the clay from the box through the bottom into the mold below.

The arm L, on leaving the lever F, immediately engages the lever G, thereby elevating the follower again to the position seen in fig. 1, which is again forced down by the next arm L, in the order of their arrangement, which, in this instance, is four times during one revolution of the wheel I, therefore filling four molds in succession at each rotation of the wheel and arms.

During the same time the filled molds are discharged from under the press-box by the slide Q referred to, which is operated as above said by the arm P, which is thrown forward by the radial arms L during the revolution of the wheel N.

The arrangement of the radial arms of the wheel N is such as to conform to that of the radial arms of the wheel I in number, position, and their revolution is so timed in relation to the movement of the follower that the slide is pushed forward at the instant that said follower begins to ascend, thereby pressing against the side of the empty mold V, fig. 5, forcing it outward against the filled mold S, which will be driven from under the press onto the table W, as indicated by the dotted lines b, fig. 5, and, as a consequence, bringing the empty mold under the press to be filled by the now descending follower, during which descent is inserted another empty mold behind that under the press, which, in like manner, will be forced under the press by the slide, and, in turn, pushing forward the now-filled mold onto the table, and so

on four times during one revolution of the wheels and arms, both of which operate relatively and conjointly in filling the molds and discharging them from under the press.

A less number than four molds may be filled during one revolution of the wheel and radial arms by elevating the arms one, two, and three, fig. 2, and extending the arms M, as indicated by the dotted lines e, also, the arms for discharging the molds must be arranged correspondingly. This change will lessen the capacity of the machine one-fourth, giving three filled molds at each revolution instead of four.

The capacity of the machine may be reduced to one-half by erecting all the arms but two; said two should be those left in line with one diameter of the wheel, so as to equalize the timely movements of the press.

The degree of pressure expended upon the molds may be graduated by the bar A', fig. 1, under which the end of the radial arms pass as they rotate, and by which they are prevented from slipping from their engagement with the lever F until the arrival of the arm to the shoulder B' of the bar. The arm then will slip over the shoulder and slide off over the end of the lever, thereby relieving the mold from further pressure.

It will be obvious that the longer the radial arm is continued in contact with the lever the greater will be the downward movement of the follower, hence, a greater pressure upon the mold will be the consequence.

The distance of the descent of the follower may be shortened, and the consequent pressure upon the molds lessened by moving the bar A' back, as indicated by the dotted lines d, by means of the adjusting-lever C', the lower end of which is held in place by a pin dropping into the holes F.

This backward adjustment of the bar allows the radial arms to slip from their engagement with the lever sooner, as the distance it may have to traverse to reach the shoulder is shortened, therefore the de-

scent of the follower and its pressure will be correspondingly less.

The ascent of the follower is actuated in a corresponding manner and time by the shoulder D' of the bar, hence, its descent and ascent is made in equal time, as the adjustment of the rod may determine.

In connection with the table W, referred to, is used a portable table E', fig. 5, mounted upon the wheels F'.

As fast as the filled molds are pushed out from under the press, they slide over the permanent table W to the portable table E', onto and down which they slide to the lower end.

The table, on being filled with molds, is then detached from the machine and wheeled off to the place for drying.

By this means much time and labor are saved in removing the molds from the machine, which is ordinarily done by hand, one at a time.

Claim.

What I claim as my invention, and desire to secure by Letters Patent, is—

1. The wheel I, provided with pivoted radial arms L M, more or less in number, substantially in the manner as described and for the purpose set forth.

2. The levers F G, as arranged, in combination with the standard E, when operated by the radial arms L M, in the manner as described and for the purpose specified.

3. The adjusting sliding bar A', as arranged in relation to and in combination with the radial arms L M, substantially as and for the purpose set forth.

4. The discharging-wheel N, provided with pivoted radial arms L' M', as arranged in relation to the wheel I and radial arms L M, and in combination with the arms P for operating the slide Q, in the manner substantially as described and for the purpose specified.
